UNITED STATES PATENT OFFICE.

ANGUS S. HIBBARD, OF MILWAUKEE, WISCONSIN.

ATOMIZER.

SPECIFICATION forming part of Letters Patent No. 310,999, dated January 20, 1885.

Application filed September 30, 1884. (No model.)

To all whom it may concern:

Be it known that I, ANGUS S. HIBBARD, of Milwaukee, in the county of Milwaukee, and in the State of Wisconsin, have invented certain new and useful Improvements in Atomizers; 5 and I do hereby declare that the following is a full, clear, and exact description thereof.

My invention relates to that class of articles known as "atomizers," and will be fully 10 described hereinafter.

In the drawings, Figure 1 is a central vertical section of my device, and Fig. 2 is a like view of a modification thereof.

A is an ordinary rubber bulb, having an 15 air-valve, a, in its lower end, or at any other suitable point, and an internally-screw-threaded collar, B, in its neck.

C is a cover that has an externally-screw-threaded neck, c, which has an aperture 20 through its center, and a circular recess on its under side to receive a centrally-perforated stopper, D, the lower end of which is inserted in the receptacle E, that contains the liquid E' to be atomized.

25 F is a tube that extends up from within the liquid-receptacle through the stopper D and cover C. The upper portion of the central perforation in the stopper D is enlarged, and a tube, G, is extended down parallel with tube F, and then bent so as to be passed out at an angle to it and open into the bulb. The outer ends of the tubes are of corresponding form to those of ordinary atomizers.

30 The cover may be of any desired form, and 35 may be provided with one or more necks on top for attaching atomizing-tubes of different forms to it.

I do not confine myself to any particular 40 form of liquid-receptacle or of stopper, as any form of either that will admit of the suspension 45 of the liquid-receptacle in the bulb by the stopper will serve my purpose.

The operation of my device is very simple. The compression of the bulb forcing the air 45 through tube G will cause it to draw the liquid from the receptacle and inject it upon the surface to be treated.

Instead of passing the tube G through the

cover and cork, I may place this tube on the outside of the bulb, and have it extend up to 50 the outlet of the tube F. In this case I would use a flexible tube, and make one end removable, so as to admit of the removal of the cover, as shown in Fig. 2. The removable end may have a downward solid projection, g, 55 passing through the cover C and into the stopper D, and this end may be pulled out when it is desired to remove the receptacle E from the bulb A; or the end g' of the flexible part of the tube G may be removed from the in- 60 flexible part for this purpose.

The receptacle E is preferably of glass, so as to show its contents and condition whenever removed from the bulb, and the tubes F G may be of glass, metal, or any material 65 preferred, and the stopper D may be of either rubber, cork, or any substance found suitable.

Having thus described my invention, what I claim as new, and desire to secure by Letters Patent, is—

1. An air-bulb inclosing a liquid-receptacle, in combination with one tube leading out from within the receptacle and another leading out from the space within the bulb, and between it and the receptacle, forming an atomizing-injector, substantially as set forth. 75

2. In an atomizer, the combination of a liquid-receptacle inclosed within a compressible air-bulb, with tubes leading, respectively, from the receptacle and air-bulb to the outside, 80 substantially as set forth.

3. The combination, in an atomizer, of a compressible bulb, a liquid-receptacle, a stopper, a threaded collar, and a corresponding cover having a recess for the stopper of the liquid-receptacle, and perforations for the atomizing-tubes, substantially as set forth. 85

In testimony that I claim the foregoing I have hereunto set my hand, at Milwaukee, in the county of Milwaukee and State of Wisconsin, in the presence of two witnesses.

ANGUS S. HIBBARD.
